UNITED STATES PATENT OFFICE.

NORMAN H. BEEBE, OF DAVENPORT, IOWA, ASSIGNOR TO LEE BROOM & DUSTER COMPANY, OF DAVENPORT, IOWA, A CORPORATION OF IOWA.

DESIGN FOR A BROOM-SHOULDER COVER.

46,423.

Specification for Design.

Patented Sept. 22, 1914.

Application filed July 2, 1914. Serial No. 848,685. Term of patent 14 years.

To all whom it may concern:

Be it known that I, NORMAN H. BEEBE, a citizen of the United States, residing at Davenport, in the county of Scott and State of Iowa, have invented a new, original, and ornamental Design for Broom-Shoulder Covers, of which the following is a specification, reference being had to the accompanying drawing, forming part thereof, in which drawing—

I claim:—

The ornamental design for a broom-shoulder cover, as shown.

NORMAN H. BEEBE.
